UNITED STATES PATENT OFFICE.

CHARLES J. ALLEN, OF MOORESTOWN, NEW JERSEY.

DESIGN FOR A GEAR-CASING.

43,399.

Specification for Design.

Patented Dec. 31, 1912.

Application filed July 27, 1912. Serial No. 711,928. Term of patent 14 years.

To all whom it may concern:

Be it known that I, CHARLES J. ALLEN, a citizen of the United States, and a resident of Moorestown, county of Burlington, and State of New Jersey, have invented a new, original, and ornamental Design for Gear-Casings, of which the following is a specification, reference being had to the illustrations shown in the accompanying drawing.

Figure 1 is a perspective view of my design for gear casings and Fig. 2 a face view thereof.

What I claim is:

The ornamental design for a gear casing substantially as shown.

CHARLES J. ALLEN.
